UNITED STATES PATENT OFFICE.

JOHN H. LONSKY AND JOHN S. McCARTHY, OF DETROIT, MICHIGAN.

WATER-HEATER.

1,100,662.

Specification of Letters Patent. Patented June 16, 1914.

Application filed June 16, 1911. Serial No. 633,570.

To all whom it may concern:

Be it known that we, JOHN H. LONSKY and JOHN S. McCARTHY, citizens of the United States of America, residing at Detroit, in the county of Wayne and State of Michigan, have invented certain new and useful Improvements in Water-Heaters, of which the following is a specification, reference being had therein to the accompanying drawing.

The invention relates to water heaters of that type in which the liquid is passed through a coil arranged within a jacket in proximity to a combustion heater and is connected at its upper and lower ends respectively with the hot water delivery and water supply connections.

It is one of the objects of the present invention to provide more complete access to this coil for purpose of cleaning, further to obtain a construction in which clogging of the coil and the consequent burning out of the same is avoided, and further to obtain an advantageous distribution of the heating surface.

With these objects in view the invention consists in various features of construction as hereinafter set forth.

In the drawings, Figure 1 is a plan view of the heater; Fig. 2 is an elevation partly in section through the middle of the jacket; Fig. 3 is a horizontal section showing the heating coil; and Figs. 4 and 5 are respectively a horizontal section and a front elevation of the connection between the coil, the jacket, and the external water pipes.

In the present state of the art, in the construction of water heaters of the coil type, it is common to increase the amount of heating surface and distribution of the same by arranging a plurality of coils connected in multiple to the external circulating pipes. With such constructions if a stoppage occurs in one of the coils a free path for circulation is still permitted through another coil, and consequently the chocked coil is very liable to be burned out. With the present construction we avoid this objection by using a single coil and at the same time the construction of this coil is such as to afford just as advantageous a distribution of the heating surface as in the multiple coil constructions. As shown more particularly in Figs. 2 and 3, A is the coil which is a compound or complex, of a plurality of coils in series with each other. These are prefer-

ably arranged in groups within the outer casing or jacket B and as shown there are three of these groups indicated respectively at C, D and E. In each group there is a complete circular convolution which then passes to a corresponding convolution in a second group and so on through the entire number of groups after which it returns to the first for a second convolution of a similar character. Thus in the entire coil the heating surface is so distributed as to be exposed to the flame and products of combustion from the burner, without any material shielding effect of one coil or convolution by another.

A further feature of our invention is the construction of the jacket by which access may be obtained to the coil for removing dust and otherwise cleaning. Heretofore, it has been customary to form jackets for coils with a door that can be opened to obtain access to the coil, and in many constructions this door constitutes one third or more of the section of the case. With our improved construction, two opposed doors are arranged so that both may be opened and together they constitute the greater part of the case, there being only a sufficient stationary part to form the door mountings, and a support for the coil.

In detail, F is a frame composed of opposite side members and top member which forms an arch about the coil. This frame is connected at its lower end to the burner G and also has connected thereto the opposite door sections H and I which together therewith complete the case or jacket. These door sections are hinged at one edge to one of the side members of the frame and at their opposite edges overlap the opposite side member of the frame to which they are secured by a suitable latch J. Thus whenever it is desired to clean the coil by opening the doors H and I, almost the entire coil is exposed and the cleaning brush may be passed through from one side to the other.

For securing the coil to the frame F so as to form a rigid mechanical support and also a water tight connection with the external pipe system, we have devised the following construction: K are slots formed in the frame F which permit of engaging the end portions L of the coil therewith. M is a nipple into which the end L of the coil is passed, said end portion having a flared

part L' engaging a corresponding seat in the nipple. This nipple M is provided with flanges N which are bolted at O to the frame. P is another nipple having a threaded engagement with the nipple M and a corresponding tapered bearing which braces the flared portion of the pipe L against the seat on the nipple M and forms a water-tight joint. Thus by the construction described, 10 the coil may be secured to the frame and a water-tight joint formed with the nipple P to which the external pipe connections are attached.

Another advantage of the construction 15 just described is that it facilitates repairs, where leaks occur in the coil. Thus it is a well known fact that the points in the coil first to give away are near the terminals, doubtless due to the fact that the stress of 20 expansion and contraction are concentrated in this location. With our construction, if a leak occurs adjacent to the end of the coil

the nipple P may be removed and the coil pipe drawn outward so as to cut-off the defective portion. The end of the tube may 25 then be flared and clamped by the nipple P against the conical seat in the nipple M, which will again render the construction water-tight.

What we claim as our invention is: 30

In a water heater a single heating coil having the successive convolutions thereof arranged with their axes staggered in relation to each other, and arranged in groups with the axes of portions of each group in 35 series with those of other groups.

In testimony whereof we affix our signatures in presence of two witnesses.

JOHN H. LONSKEY.
JOHN S. McCARTHY.
